UNITED STATES PATENT OFFICE.

EWALD ROSS, OF BARMEN, GERMANY, ASSIGNOR TO THE FIRM OF INTERNATIONALE GASGLÜHLICHT ACTIEN-GESELLSCHAFT, OF BUDAPEST, AUSTRIA-HUNGARY.

INCANDESCENT GAS-MANTLE.

1,052,622.

Specification of Letters Patent. Patented Feb. 11, 1913.

Application filed November 25, 1910. Serial No. 594,071.

To all whom it may concern:

Be it known that I, EWALD Ross, manufacturer, a subject of the Emperor of Germany, and resident of Barmen, Handelstrasse 4, Rhenish Prussia, Germany, have invented new and useful Improvements in or Relating to Incandescent Gas-Mantles, of which the following is a specification.

It is the object of the present invention 10 to provide an incandescent gas mantle the body of which or carrier for the illuminating element is formed of interlaced, knitted bands, cords, braids or the like, and which is provided with strengthening elements 15 transversely disposed to said body forming elements. These strengthening elements are in the same manner as the body formed of interlaced threads, cords or the like. The cords may be solid or tubular and the 20 threads may be interlaced, entwined or woven together so as to form a mantle body of great durability. A body of this construction is adapted to give a much brighter and more intensive light than is given by 25 mantles of the known constructions because the illuminating element is more uniformly distributed in the body and adheres more intimately to the same, thus forming an elastic structure which is less liable to 30 breakage and which produces a greatly improved light. Finally when passing the mantle through the impregnating rollers its strengthening element will not be the cause of tearing holes in the body of the mantle 35 as frequently happens in the manufacture of the customary mantles, as the tubular cords and interlaced threads forming the strengthening elements will yield elastically when passing between the rollers, said tubular cords moreover are suitably adapted 40 to receive and hold a considerable quantity of the impregnating fluid.

In the accompanying drawing:—Figure 1 shows part of a mantle body composed of 45 interlaced bands each of which is formed of

interwoven threads. Fig. 2 is a similar view showing part of a mantle body formed of interlaced bands and having strengthening elements interwoven therewith each of which is composed of interlaced threads, 50 and Fig. 3 shows in its lower portion a combination of the elements shown in Figs. 1 and 2 and in its upper portion the strengthening elements interwoven with the elements shown in Fig. 1. 55

The mantle body is composed of interlaced bands, strands or braids *a*, *b*, each of said bands being formed of interlaced threads *c*.

As shown in Fig. 2 strengthening elements *d*, *e* are provided which are disposed in the mantle body in the ordinary well known manner and each of which is composed of interlaced bands *f* formed of interlaced threads *g*. The bands are individually extensible and are formed of meshes. 60

As shown in Fig. 3 the bands *a*, *b* are interlaced with the strengthening elements *d*, *e* and the stiffening elements *f*, *g* are suitably interwoven with the first named 70 bands. The stiffening elements may also be dispensed with in the lower portion of the mantle and only be used in its upper part. 65

Whenever stiffening bands are employed and consequently loops are formed, the same 75 must be flattened by stretching the fabric upon a suitable former or mandrel.

I claim:

An incandescent gas mantle comprising a body carrier for the illuminating element, 80 interlaced, knitted bands forming said body, strengthening elements transversely to said body forming elements, and, interlaced threads for forming said strengthening elements, substantially as described.

EWALD ROSS. [L. s.]
